DESIGN FOR A JEWELLED FINGER RING

Raymond A. Ritter, Pittsburgh, Pa.

Application October 20, 1947, Serial No. 142,013

Term of patent 14 years

(Cl. D45—10)

To all whom it may concern:

Be it known that I, Raymond A. Ritter, a citizen of the United States, residing in Pittsburgh, in the county of Allegheny and State of Pennsylvania, have invented a new, original, and ornamental Design for Jeweled Finger Ring, of which the following is a specification, reference being had to the accompanying drawings, forming part thereof.

Fig. 1 is a perspective view of one side of a jeweled finger ring embodying my new design;

Fig. 2 is an enlarged plan view of a portion of the ring showing the design details;

Fig. 3 is an enlarged cross-sectional view taken on the line III—III of Fig. 2; and

Fig. 4 is a perspective view of the jeweled finger ring, showing the opposite side from that shown in Fig. 1.

I claim:

The ornamental design for a jeweled finger ring, substantially as shown.

RAYMOND A. RITTER.
